PAPER ROLL PLUG

Dana Franklin Nelson, Longview, Wash., assignor to Nelson-Ball Paper Products, Inc., Longview, Wash.

Filed Feb. 7, 1973, Ser. No. 330,314

Term of patent 14 years

Int. Cl. D8—99

U.S. Cl. D8—220

FIG. 1

FIG. 2

FIG. 3

FIG. 4

FIG. 5

FIG. 1 is a rear perspective of a paper roll plug showing my new design;

FIG. 2 is a rear end view of the same;

FIG. 3 is a front end view of the same; and

FIG. 4 is an edge view of the same.

FIG. 5 is a cross sectional view taken on line 5—5 of FIG. 2.

I claim:

The ornamental design for a paper roll plug, as shown.
